(57) **CLAIM**

The ornamental design for a multipurpose tool facilitating formation of accurate bends in electrical conduit, as shown and described.

DESCRIPTION

FIG. 1 is a perspective view of a multipurpose tool showing our new design;

FIG. 2 is a perspective view thereof as seen from an alternative angle;

FIG. 3 is side elevational view thereof as seen generally from the right in FIG. 1;

FIG. 4 is a top view thereof;

FIG. 5 is a bottom view thereof;

FIG. 6 is a front view thereof as seen from the right in FIG. 3;

FIG. 7 is a back view thereof as seen from the left in FIG. 3; and,

FIG. 8 is a side elevational view as seen from the left in FIG. 7.
